UNITED STATES PATENT OFFICE.

EDWARD A. MEYSENBURG, OF ST. LOUIS, MISSOURI, ASSIGNOR TO THE
MASCOTTE STOVE COMPANY, OF SAME PLACE.

OIL AND GAS STOVE.

SPECIFICATION forming part of Letters Patent No. 269,950, dated January 2, 1883.

Application filed March 2, 1882. (No model.)

To all whom it may concern:

Be it known that I, EDWARD A. MEYSENBURG, of St. Louis, Missouri, have made a new and useful Improvement in Oil and Gas Stoves, of which the following is a full, clear, and exact description, reference being had to the annexed drawings, making part of this specification, in which—

Figure 1. is a front elevation of the improved stove, half of the front being removed to exhibit the interior; and Fig. 2, a central vertical section.

The same letters denote the same parts.

A heating apparatus and a cooking apparatus are combined in the present construction.

A represents the improved stove. In its general outline it is an upright prism. The heat-producing device consists of one or more lamps, B B, arranged in a chamber, C, in the lower part of the stove, the lamps being suitably supported to bring the burner-tubes b b properly into relation to the slotted cones d d of the plate D. The latter divides the chamber C from the combustion-chamber E. Above the last-named chamber, and separated therefrom by the plate F, is an oven, G. There are openings f in the plate F to receive cooking utensils, the openings, when not in use, being closed by the covers f'. The heat-currents pass from the combustion-chamber through the opening or passage f², thence upward through the oven G, and thence out therefrom through the outlet g and into a flue, H, above

the oven. From the flue H the currents pass downward into the flue I. This last-named flue extends from the uppermost part of the stove downward past the oven, and the exit J is preferably not much above the level of the bottom of the oven. The various arrows indicate the course of the incoming air and of the heat-currents in their passage through the stove. A hot closet, K, is conveniently formed in the rear of the lamp-chamber, and in such relation to the wicks in cone d that its upper part is heated by the direct action of the burning wick as well as the escaping products of combustion which pass over its top. The oven has suitable doors, g', and shelves, such as g².

I claim—

1. The combination of lamp B, hot closet K, and vertically-arranged chambers of combustion E and oven G, substantially as shown and described.

2. A lamp-stove having its oven G above the chamber of combustion E, and having an opening in the lower side of said oven and another at the opposite side, in the top, at g, and a flue, H, above the oven, and a side escape-flue, I, whereby the heated and escaping products of combustion pass under and from side to side through the oven, over its top, and down its rear, all substantially as described.

EDW. A. MEYSENBURG.
